UNITED STATES PATENT OFFICE.

HAMMEL H. CARRELL, OF LUBBOCK, TEXAS, ASSIGNOR OF ONE-HALF TO SOLOMON NATHAN JACKSON, OF LUBBOCK, TEXAS.

GAS BURNER.

Application filed February 14, 1928. Serial No. 254,282.

This invention relates to burners for burning gas for heating purposes, and the burner is designed to be used in any situation where it is desired to use either natural or artificial gas as a heating agency.

The general object of the present invention is to provide a burner which will operate with very low pressure gas.

A further object is to so construct the burner that it will secure a thorough admixture of the gas with air and thus burn the gas very economically and at the same time secure a hot blue flame.

A still further object is to provide means whereby air may be drawn into the mixing tube and the gas thoroughly mixed with the air before and at its point of combustion.

My invention is illustrated in the accompanying drawing, wherein:—

20 Figure 1 is a top plan view of my improved burner;

Figure 2 is a side elevation thereof;

Figure 3 is a longitudinal section thereof.

Referring to this drawing, 10 designates a tube of any desired length and of any desired metal, which tube at one end is provided with a screw-threaded nipple 11 and a nut 12. Disposed within the nipple 11 and projecting into the tube 10 is a gas jet 13 having a relatively small bore 14, this bore not being coaxial with the axis of the tube 10 but being directed downward and forward so that the jet of gas escaping from the bore strikes the bottom of the tube 10 adjacent the forward end of the tube. This tube 10 on each side of the gas burner tip or nozzle 13 is cut away so as to provide two openings 15, and it will be noted that the tube 10 does not touch the projecting end of the tip but is spaced above and below the tip. Thus plenty of air can enter the tube 10 and immediately around the tip and in advance thereof.

In advance of the opening 15 the top of the burner is formed with an air inlet opening 16. 45 This opening is formed by cutting straight downward through the tube at the forward end of the opening and cutting downward and forward and intersecting with the vertical cut from the rear portion of the tube. 50 Thus in side elevation the opening is triangular in form. The downwardly and forwardly extending wall 17 of the opening is approximately parallel to the direction of the jet of gas issuing from the bore 14 of the tip 13 so 55 that the gas strikes the bottom of the tube 10

in advance of the opening 16 and approximately in line with the inclined wall 17.

The forward end of the tube 10 is formed with the upwardly and forwardly extended and longitudinally rounded deflector 18 which may be made integral with the tube and formed by splitting the end of the tube and then flattening the tube laterally, the lower corners of the deflector being turned over upon the lower end of the deflector and adjacent the tube so as to form the wings 19. Preferably this deflector is provided with a plurality of holes 20 through which air may enter, and attention is called to the fact that air may also enter the deflector at the openings 21 formed by the returned ends of the wings.

In the use of this invention, the jet of gas projected from the tip 13 strikes the bottom of the tube or pipe 10 and then rebounds upward. This jet of gas draws air into the tube 10 at the openings 15 and at the openings 16 and the rebounding of the jet as it strikes first upon the bottom of the tube 10, then upon the top thereof where it is deflected downward toward the base of the deflector 18, and then the deflection of the mixed air and gas upward, tends to thoroughly mix air with the gas so that in actual practice a perfectly blue flame is discharged upward and outward from the base of the deflector, this blue flame being fan-shaped and giving an intense heat. The openings 20 permit the introduction of air into the flame itself so that a thorough intermingling of the air is secured with the gas and the effect is as if the gas was forced outward under steam pressure. No adjustment is necessary for this burner and it may be used anywhere where natural or artificial gas is to be used for heating purposes. It will not backfire and may be used for boilers, hot air furnaces, ranges and in other places of like character.

I claim:—

1. A gas burner of the character described comprising a tube, a gas jet entering one end of the tube and having its axis disposed at an acute angle to the axis of the tube whereby the gas discharged from the jet impinges at a place against the wall of the tube, air openings disposed rearward of said place where the gas jet strikes, and a deflector disposed angularly with respect to the tube and against which the intermingled jet of gas and air strikes, the deflector adjacent the tube be-

ing formed with inwardly turned wings defining air openings.

2. A gas burner of the character described comprising a tube, a gas jet entering one end 5 of the tube and having its axis disposed at an acute angle to the axis of the tube whereby the gas discharged from the jet impinges at a place against the wall of the tube, air openings disposed rearward of said place where 10 the gas jet strikes, and a deflector disposed angularly with respect to the tube and against which the intermingled jet of gas and air strikes, the deflector adjacent the tube being formed with inwardly turned wings defining 15 air openings, the body of the deflector also having air openings.

3. A gas burner of the character described comprising a tubular member having a gas jet entering one end thereof, the longitudinal 20 axis of the jet being disposed at a slight angle to the longitudinal axis of the tube whereby the gas discharged from the jet will strike

the wall of the tube, the tube adjacent the jet on each side thereof being formed with air inlet openings and in advance of these inlet 25 openings being formed in its top wall with an air inlet opening defined by two walls one extending downward and forward into the tube and one extending transversely, said last named opening being disposed rearward of 30 the place where the gas strikes the wall of the tube, the forward end of the tube being formed with an integral upwardly and outwardly extending, longitudinally curved deflector, the inner corners of the deflector being 35 bent over and inward to form wings extending diagonally outward from the mouth of the tube and defining air inlet openings, the body of the deflector being formed with air inlet openings.

In testimony whereof I hereunto affix my signature.

HAMMEL H. CARRELL.
